CLAIM

The ornamental design for a combined tooth and tongue brush with timing device, as shown and described.

DESCRIPTION

FIG. 1 is a front elevational view of the combined tooth and tongue brush with timing device of the present invention; FIG. 2 is a rear elevational view of the combined tooth and tongue brush with timing device of FIG. 1;

FIG. 3 is a left side elevational view of the combined tooth and tongue brush with timing device of FIG. 1; the right view being a mirror image thereof;

FIG. 4 is a top plan view of the combined tooth and tongue brush with timing device of FIG. 1; and,

FIG. 5 is a bottom plan view of the combined tooth and tongue brush with timing device of FIG. 1.
